UNITED STATES PATENT OFFICE.

VIRGIL C. COX, OF PADUCAH, KENTUCKY.

OIL-CAN.

1,092,433.

Specification of Letters Patent.

Patented Apr. 7, 1914.

Application filed November 19, 1913. Serial No. 801,836.

To all whom it may concern:

Be it known that I, VIRGIL C. Cox, a citizen of the United States, residing at Paducah, in the county of McCracken and State of Kentucky, have invented certain new and useful Improvements in Oil-Cans, of which the following is a specification.

The present invention relates to improvements in oil cans of the compartment type, and is designed particularly for storing oils convenient for use.

The primary object of the invention is the provision of an oil can having a plurality of compartments, and having a member common to all of the compartments through which oil may pass from a selected compartment as desired.

The invention consists in certain novel features of construction and combinations and arrangements of parts including a rotary plug constructed to form a valve adapted for use with any selected one of the plurality of compartments.

In the accompanying drawings I have illustrated one complete example of the physical embodiment of my invention constructed according to the best mode I have so far devised for the practical application of the principles.

Figure 1 is a vertical central sectional view of the oil can embodying my invention, some parts being shown in elevation. Fig. 2 is a horizontal sectional view of Fig. 1 on line 2—2.

The can as shown in Fig. 2, in the preferred embodiment, is rectangular in cross section, and comprises compartments 1, 2, 3, and 4 in which kerosene oil, gasolene, and "foot oil", respectively, may be contained.

In Fig. 2 it will be noted that the compartments 1 and 2 are formed by one piece of metal bent to proper shape, the seam being soldered at 5 between the compartments 2 and 3. The compartments 2 and 4 are formed by plates 6 and 7, respectively, which at their ends are soldered to the corners of the compartments 1 and 2, as at 8. The walls 9, 10, 11, and 12 converge at the center of the can, and form, with the outside

walls, the four compartments, each of which is rectangular in cross section. In the upper end of the can the top 12 is centrally perforated for the reception of a sleeve 13, the latter being formed with an annular flange 14 that is soldered to the top 12 of the can. This sleeve 13 is provided with a ta-

pering bore at its upper end which has four outlets as 15, 16, 17, and 18 opening each one into a compartment of the can. The tapering bore of the sleeve is adapted to receive the correspondingly tapered plug 19 which is bored out at 20, and has a port 21 which is adapted to register with a selected one of the openings 15, 16, 17, or 18. This plug forms a valve to close three of the openings, and to open the fourth, and it is provided on its lower end with a stem 22 which projects through a perforated washer 23 resting against an annular flange or shoulder 24 of the sleeve 13. A spring 25 surrounds the stem 22, and bears upon a second washer 26 which is held on the stem by a key 27. In this manner the plug is held in its tapered seat because of the pressure of the spring downwardly upon the washer 26, from the washer 23. Below the stem the open end of the sleeve or bushing 13 is closed by a plate 28, and the upper end of the tapering plug has a spout 29 screwed therein by means of the threads 30. The top 12 of the can is provided with markings to indicate the stopping point for the plug, when it is rotated to register with a selected compartment opening.

In using the oil can the plug, which is roughened or gnarled at the head or flange 31, may be rotated and is revolved in the tapering seat of the bushing until the port 21 is made to register with the selected can opening 15, 16, 17, or 18, the port being shown in Fig. 1 as registering with the opening 18 from compartment 2, so that cylinder oil may be expelled from the spout 29. The oil is expelled from the can by squeezing upon the side of the compartment from which it is desired to expel the oil, as will be readily understood.

From the above description taken in connection with my drawings it will be understood that I have provided a durable, compact, and easily operated oil can which is simple in construction and comparatively cheap in production, and free from devices or elements that are likely to become disarranged, or get out of order.

While I have indicated the four different kinds of oil that may be used in the can, it will, of course, be understood that other kinds other than those mentioned may be used, and other liquids other than oils may be used if desired and convenient.

Having thus described my invention, what

I claim as new and desire to secure by Letters Patent, is:—

1. The combination with an oil can having a plurality of compartments and a hollow bushing having a single opening to each compartment, of a plug revoluble in said bushing and having a port adapted to register with any one of said openings, a spout in the plug, and a spring holding the plug to its seat in the bushing.
2. The combination with an oil can having a plurality of compartments and a hollow bushing having an opening into each compartment, of a revoluble plug having a

port to engage any one of said openings, 15 a stem on the plug, a perforated washer surrounding the stem and seated against the bushing, a spring surrounding the stem, and a washer at the end of the stem, said spring bearing upon said two washers to hold the 20 plug in the bushing.

In testimony whereof I affix my signature in presence of two witnesses.

VIRGIL C. COX.
